THUMB TURN FOR A LOCK

Marron Kendrick, Atherton, Calif., assignor to
Schlage Lock Company

Filed Apr. 7, 1971, Ser. No. 132,268

Term of patent 14 years

Int. Cl. D8—07

U.S. Cl. D8—108

FIG. 4

FIG. 2

FIG. 1

FIG. 3

FIG. 5

FIG. 1 is a front elevation of a thumb turn for a lock, showing my new design;

FIG. 2 is a left side elevation of the article of FIG. 1;

FIG. 3 is a right side elevation of the article of FIG. 1;

FIG. 4 is a top plan of the article of FIG. 1; and

FIG. 5 is a bottom plan of the article of FIG. 1.

The rear elevation of the article is plain.

I claim:

The ornamental design for a thumb turn for a lock, as shown and described.
